INKING MECHANISM FOR ROTARY PRINTING PRESSES

Hans J. Luehrs, Westerly, R. I., assignor to C. B. Cottrell & Sons Company, Westerly, R. I., a corporation of Delaware

Application April 2, 1936, Serial No. 72,284

5 Claims. (Cl. 101—350)

This invention is particularly directed to inking mechanisms for high speed rotary printing presses in which low and high speed ink distributing rolls are used because of the necessarily low speed of the fountain roll.

This invention comprises, generally, a ductor roll interposed between the fountain roll and one of the low speed ink distributing rolls, and two additional ductor rolls interposed between one of the low speed distributing rolls and a high speed distributing roll, said two ductor rolls being operated to alternately contact with the low speed distributing roll and with the high speed distributing roll for ensuring an ample and even supply of ink to the high speed distributing roll.

One object of my invention is to provide means whereby both ends of each of the said ductor rolls are operatively connected to the ductor roll vibrating means to obviate the use of the usual shaft cam and spring means operatively connected to one end only of each of the ductor rolls, which means tends to cause a twisting of the ductor shafts and bouncing of the ductor rolls when the press is driven at high speeds.

Another object is to provide means whereby the said ends of the ductor rolls are independently adjustable radially and/or laterally to bring them into accurate positions with respect to their coating rolls.

Still further object is to provide common cams for controlling the operation of the corresponding ends of the two ductor rolls interposed between a low speed distributing roll and a high speed distributing roll.

A practical embodiment of my invention is represented in the accompanying drawings, in which

Fig. 1 represents a detail top plan view of that part of an inking mechanism which includes my invention;

Fig. 2 represents a detail side view of the same;

Fig. 3 represents a detail cross section, taken in the plane of the line III—III of Fig. 2, looking in the direction of the arrows; and

Fig. 4 represents a detail section, taken in the plane of the line IV—IV of Fig. 2, looking in the direction of the arrows.

The ink fountain is denoted by 1 and its fountain roll by 2, which roll may be driven in the usual manner and at a low speed from the rotary crank disc 3 through the connecting rod 4, oscillating lever 5 and its pawl and ratchet connection 6, 7 with the shaft 8 of the fountain roll, which crank disc 3 is carried by the cam shaft 9.

The low speed ink distributing rolls are denoted

by 10, 11, 12 and the high speed distributing roll by 13.

A single ductor roll 14 is vibrated between the low speed fountain roll 2 and low speed distributing roll 10. Two ductor rolls 15, 16 are vibrated between the low speed distributing roll 12 and the high speed distributing roll 13.

Both ends of all three of these ductor rolls are operatively connected to their respective vibrating means and both ends of these ductor rolls are also independently adjustable radially and/or laterally with respect to their coating rolls.

Each end of the shaft 17 of the ductor roll 14 is rotatably mounted in an arm 18 of a two armed lever 19 pivoted on a stud 20 projecting from a bracket 21 pivoted to swing on a bolt 22 projecting from the frame 23. The second arm of this rock lever 19 is denoted by 24. This bracket 21 is adjustable to move the ductor roll 14 inwardly and outwardly by providing the bracket with a concentric slot 25 through which a bolt 26 projects from the frame 23. A swinging nut 27 on the bolt 26 is engaged by the threaded shank of an adjusting screw 28 rotatably mounted on the bracket 21. Each lever 19 is rocked from a box cam 29 carried by one end of the shaft 9 as follows: A two armed lever 30 is also pivoted on the bracket stud 20, one arm 31 of which lever carries a stud or roller 32 which travels in the groove 33 of the box cam 29, the other arm 34 of which lever lies adjacent to the arm 24 of the ductor roll lever 19. The said arm 34 is adjustably connected to the arm 24 to permit lateral adjustment of the ductor roll 14 by providing the arm 24 with a stud bolt 35 projecting through a slot in the arm 34. Oppositely disposed adjusting screws 36, 37 are carried by the arm 34 in position to engage the opposite sides of the stud bolt 35 whereby the adjustment of these screws will change the relative positions of the arms 24 and 34 of the levers 19 and 30 and thereby the position of the ductor roll 14.

The means for mounting, adjusting and operating the ductor rolls 15 and 16 which are vibrated between the low speed distributing roll 12 and the high speed distributing roll 13 are quite similar to the means for mounting, adjusting and operating the ductor roll 14 which is vibrated between the low speed fountain roll 2 and the low speed distributing roll 10, except that a single box cam 38 located at each end of the cam shaft 39 controls the operation of the corresponding ends of both of the said ductor rolls 15 and 16.

This box cam 38 has a groove 40 at opposite

points within which travel the studs or rollers 41, 42 carried by the arms 43, 44 of the two cam operated levers pivoted on studs 45, 46 projecting from their respective adjustable brackets 47, 48 pivoted at 49, 50 to the frame 23. The outer ends of these brackets have concentric grooves 51, 52 through which project studs 53, 54 from the frame 23. Nuts 55, 56 are pivoted on the studs, which nuts are engaged by the threaded shanks of adjusting screws 57, 58 rotatably mounted in lugs 59, 60 projecting from the said brackets 47, 48.

The ductor roll levers are also pivoted on the bracket studs 45, 46, the corresponding ends of the ductor rolls being rotatably mounted in the arms 61, 62 of the said ductor roll levers. The second arms 63, 64 of the ductor roll levers are operatively connected to the second arms 65, 66 of the cam operated levers through the following 20 adjusting means:

The arms 65, 66 of the cam operated levers carry studs 67, 68 which project through the arms 63, 64 of the ductor roll levers, the opposite sides of which studs 67, 68 are engaged by adjusting screws 69, 70 and 71, 72 respectively.

The low and high speed distributing rolls and the cam shafts may be operatively connected through the train of gears 73, 74, 75, 76, 77, 78, 79, 80 and 81.

From the above description it will be seen that I have provided means whereby each end of each of the ductor rolls may be adjusted radially and/or laterally to bring the ductor roll into exact contact throughout its length with its coacting rolls as the ductor roll is vibrated, even though the shape and size of the ductor roll be changed due to the use of the ductor roll. These adjustments of the ductor rolls ensure the even transfer of the ink in the desired amounts from one 40 of its coacting rolls to the other of its coacting rolls.

It will also be seen that the positive operation of the ductor roll levers at both ends of each ductor roll prevents torsional strain of the eliminated ductor roll shaft which would tend to twist the same. This positive operation of both ends of each ductor roll also ensures its even and positive movement and eliminates the bouncing of the roll which is liable to happen where the roll is operated at high speeds under a shaft cam and spring control at one end of the roll.

The means for mounting, vibrating and adjusting the ductor roll 14 which is shown and described, but not claimed herein, forms the subject matter of my copending application filed of even 55 date herewith, its Serial No. being 72,283.

It is evident that various changes may be resorted to in the construction, form and arrangement of the several parts without departing from the spirit and scope of my invention, and hence 60

I do not intend to be limited to the particular embodiment herein shown and described, but what I claim is:

1. In an inking mechanism for rotary printing presses, a frame, two ductor rolls mounted on separate axes at each side of the frame, and means at each side of the frame operatively connected to corresponding ends of said ductor rolls at each side of the frame for vibrating them in opposite directions, each of said means comprising a cam and two levers operated thereby. 5

2. In an inking mechanism for rotary printing presses, a frame, a pair of ductor roll levers at each side of the frame, two ductor rolls mounted 15 at their opposite ends in their respective levers, and means at each side of the frame operatively connected to corresponding ends of said ductor rolls at each side of the frame for vibrating them in opposite directions, each of said means comprising a cam and two levers operated thereby and connected to their respective ductor roll levers. 20

3. In an inking mechanism for rotary printing presses, a frame, a pair of ductor roll levers at each side of the frame, two ductor rolls mounted 25 at their opposite ends in their respective levers, and means at each side of the frame operatively connected to corresponding ends of said ductor rolls at each side of the frame for vibrating them in opposite directions, each of said means comprising a cam and two levers operated thereby and adjustably connected to their respective ductor roll levers. 30

4. In an inking mechanism for rotary printing presses, a frame, two pairs of brackets independently adjustable thereon at opposite sides thereof, two pairs of ductor roll levers pivoted on said brackets, two ductor rolls mounted at their opposite ends in their respective levers, and means at each side of the frame operatively connected to the corresponding ends of said ductor rolls at each side of the frame for vibrating them in opposite directions, each of said means comprising a cam and two levers operated thereby and connected to their respective ductor roll levers. 35

5. In an inking mechanism for rotary printing presses, a frame, two pairs of brackets independently adjustable thereon at opposite sides thereof, two pairs of ductor roll levers pivoted on said brackets, two ductor rolls mounted at their opposite ends in their respective levers, and means at each side of the frame operatively connected to the corresponding ends of said ductor rolls at each side of the frame for vibrating them in opposite directions, each of said means comprising a cam and two levers operated thereby and adjustably connected to their respective ductor roll levers. 50

HANS J. LUEHRS.
